UNITED STATES PATENT OFFICE.

HENRY SPENGLER, OF NEW YORK, N. Y.

CLOSURE.

1,289,947.

Specification of Letters Patent. Patented Dec. 31, 1918.

Application filed January 8, 1914. Serial No. 811,013.

To all whom it may concern:

Be it known that I, HENRY SPENGLER, a citizen of the United States of America, and resident of New York, in the county of New York and State of New York, (whose post-office address is No. 45 Broadway, New York, N. Y.,) have invented certain new and useful Improvements in Closures, of which the following is a specification.

10 This invention relates to caps or closures, particularly adapted for use as bottle closures, though their use is not limited to this relation.

One of the objects of the invention is to 15 produce a device of the kind referred to which is readily put into place, which effectually accomplishes its sealing or covering function, and which may be removed without the use of any tools whatsoever.

20 The invention embodies certain improvements upon the devices described and claimed in my U. S. Patent No. 1,074,907 granted to me October 7th, 1913, and therefore provides a bottle cap having a central 25 resilient portion which may be bulged to one side of a plane and yieldable under pressure said cap having means gripped to the bottle mouth while the said bulge is maintained and released therefrom when the bulged portion is depressed, and the said bulged portion being capable of springing or being 30 brought back from the said releasing position.

The invention also contemplates, in addition to the features last above mentioned, means whereby the manual actuation of the cap is rendered more easy.

35 In the accompanying drawings which are to be taken as a part of this specification, 40 and in which I have shown merely preferred forms of embodiments of the invention, Figure 1 is a perspective view of a form of the invention showing a cam-lever means for actuating the cap; Fig. 2 is a central vertical 45 section illustrating the subject matter of Fig. 1, and showing two positions of the lever in full and dotted lines, respectively, and Fig. 3 is a central sectional view illustrating a form of cap with a central knob for depressing or 50 raising the central bulge.

Referring to the numerals on the drawings and particularly Figs. 1 and 2, 1 indicates a cap comprising a disk of resilient metal, having a set causing it to bulge slightly in the 55 center, as indicated at 2, and having peripheral fingers 3 which may be defined by slits

4 cut in the periphery of the disk. Diametrically opposite one of these fingers 3 are turned up, as indicated at 6, and these turned-up members 6 are apertured to provide bearings for a cam-lever 7, which lever has a U-shaped part for engagement by the fingers of the user, and can portions 8 which are intended to contact with the upwardly bulged portion of the cap, so that when the 60 lever is brought to the position shown in full lines in Fig. 2, the bulge is depressed, and when the lever lies in the position shown in Fig. 1 and in dotted lines in Fig. 2, the bulge is permitted to assume the dotted line position shown in Fig. 2. It will be understood that when the lever is in the position shown in Fig. 1, the cap, if it be in position on a bottle, will be held tightly thereon, by reason of the fact that the fingers 3 grip the 65 bottle mouth tightly; but when the lever is raised to the full line position of Fig. 2, by reason of the depression of the bulge of the cap, the fingers are caused to spread and are thereby released from the bottle mouth. 70

75 Referring now to Fig. 3, there is shown a cap generally similar to that shown in my aforesaid patent and to the caps shown in Figs. 1 and 2 of the present drawings, but the said cap is provided with a knob 10, secured to the central part of the cap. By means of this knob the user may easily depress or raise the bulge of the cap, to release or lock the same from or to the bottle mouth. With respect to the cap shown in Fig. 3, as well as 80 to those shown in the other two figures, it is to be understood that the central disk portion may be so formed that the bulge may be sprung to either one of two positions, above and below the plane respectively, so that the 85 bulge will remain in either one of those two positions to which it may be sprung.

90 As many changes could be made in the above construction and many apparently widely different embodiments of this invention could be made without departing from the scope thereof, it is intended that all matter contained in the above description or 95 shown in the accompanying drawing shall be interpreted as illustrative and not in a limiting sense. It is also to be understood that the language used in the following claims is intended to cover all of the generic and specific features of the invention herein described and all statements of the scope of the 100 invention which as a matter of language, might be said to fall therebetween.

Having thus described my invention, what I claim as new and desire to secure by Letters Patent, is:

1. A cap for bottles or the like having a central portion and separated fingers depending therefrom and integral therewith, said central portion having a permanent set causing it to bulge outward when said fingers are in gripping position, said fingers being movable from the gripping position by pressing the bulge inward, and means carried by the cap for depressing the bulge, said means also constituting a handle for bodily removing the cap from the bottle
- 10
- 15
2. A cap for bottles or the like having a central portion and separated fingers depending therefrom and integral therewith, said central portion having a permanent set causing it to bulge outward when said fingers are in gripping position, said fingers being movable from the gripping position by pressing the bulge inward, and a finger piece acting against said central portion for depressing the bulge, said finger piece also constituting a means whereby the cap may be bodily removed from the bottle.
- 20
- 25
3. A cap for bottles or the like having a central portion and separated fingers depending therefrom and integral therewith, said central portion having a permanent set causing it to bulge outward when said fingers are in gripping position, said fingers being movable from the gripping position by pressing the bulge inward, and a lever pivotally secured to the cap having a means
- 30
- 35

associated therewith for depressing the bulge when the lever is in a raised position.

4. A cap for bottles or the like having a central portion and separated fingers depending therefrom and integral therewith, said central portion having a permanent set causing it to bulge outward when said fingers are in gripping position, said fingers being movable from the gripping position by pressing the bulge inward, and a U shaped lever pivotally secured to the cap, said lever provided with cammed faces at its ends arranged to coact with the bulged portion and depress the same when the lever is raised.

40

45

5. A cap for bottles or the like having a central portion and separated fingers depending therefrom and integral therewith, said central portion having a permanent set causing it to bulge outward when said fingers are in gripping position, said fingers being movable from the gripping position by pressing the bulge inward, the material of the cap being resilient so that the central portion tends to spring to its outward bulged position when brought approximately thereto, and means carried by the cap for depressing the bulge.
